X-RAY SYSTEM FOR VARYING INTENSITY X-RAY BEAMS

Joseph Lempert, Bloomfield, N. J., assignor to
Westinghouse Electric & Manufacturing Com-
pany, East Pittsburgh, Pa., a corporation of
Pennsylvania

Application August 19, 1942, Serial No. 455,319

5 Claims. (Cl. 250—100)

The present invention relates to X-ray systems and has particular reference to such a system wherein the quality of the generated beam of X-rays is varied as desired at any given wattage to produce a radiograph of optimum contrast.

It has long been recognized that since an X-ray film or radiograph and a fluoroscopic image are essentially shadow pictures, the quality of the radiograph or image depends on varying rates of absorption and transmission of X-rays of different materials through which the beam passes. Moreover, the high voltage short wavelength X-radiation, commonly called "hard" X-rays, are the most penetrating; but from the standpoint of contrast on a radiograph or image, it is desirable in many instances to maintain a very appreciable proportion of low voltage long wavelength and low penetrating X-radiations called the "soft" X-rays.

Accordingly, the X-ray tube should have a low filtration in the glass walls of the envelope, and the use of filters to filter out low kilovoltage long wavelength X-rays produced from parts of the tube other than the focal spot is undesirable from the standpoint of optimum contrast. Yet the quality of an X-ray beam is fixed by the wave form of the voltage applied thereto which more or less determines the ratio of the long and short wavelengths of the X-radiations for a given kilovoltage. The use of filters, however, serves not only to cut off more and more of the low kilovoltage long wavelength or soft X-radiations frequently desired to produce optimum contrast on the resulting radiograph or fluorescent screen, but also decreases the short wavelength X-radiations. Moreover, since such filters absorb a very large percentage of the long wavelength X-radiations, a considerable decrease in the ratio of the long wavelength to the short wavelength X-radiations results as well as reducing the total X-ray output.

It is accordingly an object of the present invention to provide an X-ray system wherein the ratio of long wavelength X-radiations to the short wavelength X-radiations is increased.

Another object of the present invention is the provision of an X-ray system wherein the potential supplied to the X-ray tube is intermittently varied to increase the ratio of long wavelength X-radiations to the short wavelength X-radiations for the purpose of producing a radiograph or fluoroscopic image of optimum contrast.

Still further objects of the present invention will become obvious to those skilled in the art

by reference to the accompanying drawing wherein:

Fig. 1 is a diagrammatic illustration of an X-ray system showing one embodiment of the present invention;

Fig. 2 is a graphic illustration showing the distribution curve of an X-ray beam produced by different kilovoltages;

Fig. 3 is a partial diagram of the same circuit arrangement as shown in Fig. 1 but showing a further modification which the present invention may take;

Fig. 4 is a graphic illustration of the wave-form of the voltage as produced by the X-ray system as shown in both Figs. 1 and 3, and

Fig. 5 is a graphic illustration of the customary wave-form of the voltage heretofore produced in an X-ray system.

Referring now to the drawing in detail, the system as illustrated in Fig. 1 comprises an energizing transformer 5, the primary winding 6 of which is connected to the customary sixty-cycle domestic source of a potential of 115-230 volts. The high voltage secondary winding 7 is grounded in the center at 8 and one end thereof is connected to the anode and cathode, respectively, of a pair of rectifying valve tubes 9 and 10. Similarly, the opposite end of the secondary winding 7 is connected to the anode and cathode, respectively, of a second pair of rectifying valve tubes 12 and 13.

As shown, the anodes of the rectifying valve tubes 10 and 13 are connected to the cathode of an X-ray tube 14, while the cathodes of the rectifying valve tubes 9 and 12 are connected to the anode of the X-ray tube. Since each of the rectifying valve tubes, as well as the X-ray tube, is provided with thermionic cathodes which are heated to an electron-emitting temperature prior to application of energy, a low voltage transformer 15 is provided from which the rectifying valve tubes 9, 10, and 12 derive their cathode heating energy, with the primary winding of this transformer 15 being connected to the same source of domestic potential as that of the high tension transformer 5.

A similar low voltage transformer 16 is provided for supplying heating energy to the cathode of the rectifying valve tube 13 with the primary winding thereof being connected through an adjustable resistance 17 to the source of domestic potential. Likewise, a low voltage transformer 18 provides cathode heating energy for the X-ray tube 14 and it too is connected through an adjustable resistance 19 to the same source of do-

mestic potential as the other transformers so that the energy passed by the X-ray tube can be controlled.

Accordingly, a full wave rectifying arrangement is provided whereby the X-ray tube 14 is energized by a unidirectional potential during the entire alternating current cycle of the domestic source of supply. Assuming the adjustable resistance 17 connected to the transformer 16 is set so as to be cut out of the circuit and a suitable switch (not shown) for connecting the primary winding 6 and the primaries of the transformers 15, 16 and 18 to the domestic supply source, is closed, a high unidirectional potential will be impressed across the X-ray tube which will have a sinusoidal wave-form as shown in Fig. 5 wherein the ordinate represents kilovoltage and the abscissa time in fractions of a second. Thus this potential will all be in one direction through the X-ray tube but will follow the sixty cycle frequency of the domestic source of supply.

Moreover, the generated X-ray beam will follow the various curves as shown in Fig. 2 for the particular kilovoltage applied to the X-ray tube. From this curve it obviously follows that the higher the kilovoltage, the higher the intensity of the short wavelength (hard) penetrating X-radiations and the greater their ratio to the longer wavelength (soft) low potential X-radiations over the range of 20 to 50 kilovolts as shown in Fig. 2. The addition of filters in an effort to vary the quality of the beam serves only to cut off more and more of the lower voltage long wavelength X-radiations and in no way increases them so that contrast in the radiograph is not improved and, in fact, is decreased as hereinbefore mentioned.

In accordance with the present invention the ratio of the long wavelength X-radiations to the short wavelength X-radiations is increased, thus producing optimum contrast in the radiograph or fluoroscopic image. To this end the potential supplied to the X-ray tube 14 is varied during one half wave of the alternating current cycle, or one one hundred and twentieth of a second, from the potential supplied to the X-ray tube during the remaining half wave of the alternating current cycle. Such may be accomplished by adjustment of the variable resistance 17 which controls the cathode heating current for the valve tube 13 as shown in Fig. 1 or by similar adjustment of an adjustable resistance 20 connected in series with the discharge circuit which includes the anode and cathode of the rectifying valve tube 13 as shown in the modification of Fig. 3.

By adjustment of the resistance 17 the heating current for the rectifying valve tube 13 is controlled and hence its temperature. Since the cathode heating temperature can be employed to control the potential drop across this rectifying valve tube 13 and the latter is operative to pass energy to the X-ray tube 14 only during one half wave of the alternating current cycle, the potential can be varied to any desired value from that of the potential drop across the oppositely connected rectifying valve tubes 10 and 12 which pass energy only during the remaining half wave of the alternating current cycle and the cathode heating temperature of which are not adjustable.

The same result is obtained by suitable adjustment of the resistance 20 connected in series with the rectifying valve tube 13 as shown in Fig. 3. However, in this figure, which shows the arrangement of the valve tubes in the same way as that of Fig. 1 and which for illustrative purposes con-

nected to the remaining elements of the circuit of Fig. 1 at the points 22, 23, 24, and 25, the adjustable resistance 20 is in series with the rectifying valve tube 13 and is thus subjected to high voltage with respect to ground. For this reason it is not as preferable as the arrangement of Fig. 1 since, if adjusted during operation, the control knob should be insulated or grounded so that no danger of high voltage shock will result to the operator.

Adjustment of either the resistance 17 or the resistance 20 will, as above noted, cause a variation in the potential supplied to the X-ray tube 14 during one half-wave of the alternating current cycle when the rectifying valve tubes 9 and 13 are conducting, from the potential supplied to the X-ray tube 14 during the remaining half wave when the rectifying valve tubes 10 and 12 are conducting energy. Assuming that the transformer 5 is set so that it would normally supply 80 kilovolts to the X-ray tube 14 and either the resistance 17 or 20 is adjusted to a kilovoltage of say 40, the potential wave form supplied to the X-ray tube 14 will be as shown in Fig. 4 where again the ordinate represents kilovoltage and the abscissa time.

As shown in Fig. 4 during the half wave of the alternating current cycle when the rectifying valve tubes 10 and 12 are conductive, which at the frequency of sixty cycle of the domestic supply source would be every one one hundred and twentieth of a second, substantially the full potential of 80 kilovolts is impressed upon the X-ray tube. By reference now to Fig. 2, it will be observed that at this high kilovoltage of 80 (which, although not shown, would be greater than the 50 kilovolt curve shown in Fig. 2) the ratio of the long wavelength X-radiations to the short wavelength lower voltage X-radiations is one value. During the remaining half wave of the alternating current cycle when the rectifying valve tubes 9 and 13 are conductive, the potential drops to 40 kilovolts due to the adjustment of the resistance 17 or 20 as shown in Fig. 4.

By comparing this latter kilovoltage with the 30 kilovolt distribution curve of Fig. 2, it will be noted that the ratio of the long wavelength X-radiations to the short wavelength X-radiations is of an entirely different value than it was at the 80 kilovolt cycle, with the percentage of the short wavelength high voltage X-radiations being much less than the longer wavelength low voltage X-radiations at 40 kilovolts. Accordingly, during the entire alternating current cycle which includes both the 80 kilovolt and 40 kilovolt X-ray distribution, the ratio of the long wavelength low voltage X-radiations to the short wavelength high voltage X-radiations is increased, thus producing optimum contrast in the radiograph or fluoroscopic image.

It thus becomes obvious to those skilled in the art that an X-ray system is herein provided in which the potential supplied to an X-ray tube is intermittently varied during the alternating current cycle to increase the ratio of long wavelength low voltage X-radiations to the short wavelength high voltage X-radiations, thereby producing optimum contrast in the radiograph. Moreover, the roentgenologist can select any desired relationship of kilovoltages which produce for him the optimum contrast desired.

Although several embodiments of the present invention are shown and described, it is to be understood that other modifications thereof may

be made without departing from the spirit and scope of the appended claims.

I claim:

1. An X-ray system for varying the quality of a generated beam of X-rays comprising an X-ray tube, a source of alternating current electrical energy for energizing said tube, rectifying valve tubes for converting the alternating current into unidirectional current prior to its transmission to said X-ray tube, and means electrically associated with at least one of said valve tubes and operable to cause a variation in the magnitude of the potential passed by the latter during one half wave of the alternating current cycle from the magnitude of the potential passed by the other of said valve tubes during the remaining half wave of the cycle to cause an increase in the ratio of long wavelength X-radiations to the short wavelength X-radiations generated by said X-ray tube in order to produce a radiograph of optimum contrast.

2. An X-ray system for varying the quality of a generated beam of X-rays comprising an X-ray tube, a source of alternating current electrical energy for energizing said tube, rectifying valve tubes provided with thermionic cathodes heated to an electron-emitting temperature for converting the alternating current into unidirectional current prior to its transmission to said X-ray tube, and means for varying the current supplied to the thermionic cathode of one of said rectifying valve tubes to cause a variation in the magnitude of the potential passed by the latter during one half wave of the alternating current cycle from the magnitude of the potential passed by the other of said valve tubes during the remaining half wave of the alternating current cycle to cause an increase in the ratio of long wavelength X-radiations to the short wavelength X-radiations generated by said X-ray tube in order to produce a radiograph of optimum contrast.

3. An X-ray system for varying the quality of a generated beam of X-rays comprising an X-ray tube, a source of alternating current electrical energy for energizing said tube, rectifying valve tubes provided with thermionic cathodes heated to an electron-emitting temperature for converting the alternating current into unidirectional current prior to its transmission to said X-ray tube, and a rheostat for varying the cur-

rent supplied to the thermionic cathode of one of said rectifying valve tubes to cause a variation in the magnitude of the potential passed by the latter during one half wave of the alternating current cycle from the magnitude of the potential passed by the other of said valve tubes during the remaining half wave of the alternating current cycle to cause an increase in the ratio of long wavelength X-radiations to the short wavelength X-radiations generated by said X-ray tube in order to produce a radiograph of optimum contrast.

4. An X-ray system for varying the quality of a generated beam of X-rays comprising an X-ray tube, a source of alternating current electrical energy for energizing said tube, rectifying valve tubes for converting the alternating current into unidirectional current prior to its transmission to said X-ray tube, and an impedance device connected in a series circuit with one of said rectifying valve tubes and operable to vary the magnitude of the potential passed by the latter during one half wave of the alternating current cycle from the magnitude of the potential passed by the other of said rectifying valve tubes during the remaining half wave of the alternating current cycle to cause an increase in the ratio of long wavelength X-radiations to the short wavelength X-radiations generated by said X-ray tube in order to produce a radiograph of optimum contrast.

5. An X-ray system for varying the quality of a generated beam of X-rays comprising an X-ray tube, a source of alternating current electrical energy for energizing said tube, rectifying valve tubes for converting the alternating current into unidirectional current prior to its transmission to said X-ray tube, and an adjustable resistance connected in series with one of said rectifying valve tubes and operable to vary the magnitude of the potential passed by the latter during one half wave of the alternating current cycle from the magnitude of the potential passed by the other of said rectifying valve tubes during the remaining half wave of the alternating current cycle to cause an increase in the ratio of long wavelength X-radiations to the short wavelength X-radiations generated by said X-ray tube in order to produce a radiograph of optimum contrast.

JOSEPH LEMPERT.
